[57] CLAIM

The ornamental design for an air valve, as shown and described.

DESCRIPTION

FIG. 1 is a perspective view of an air valve showing my new design in the closed configuration;
FIG. 2 is a top plan view thereof;
FIG. 3 is a left side elevational view thereof;
FIG. 4 is a right side elevational view thereof;
FIG. 5 is a front elevational view thereof;
FIG. 6 is a rear elevational view thereof;
FIG. 7 is a bottom plan view thereof;
FIG. 8 is a perspective view of an air valve showing my new design in the valve open configuration;
FIG. 9 is a top plan view thereof;
FIG. 10 is a left side elevational view thereof;
FIG. 11 is a right side elevational view thereof;
FIG. 12 is a front elevational view thereof;
FIG. 13 is a rear elevational view thereof; and,
FIG. 14 is a perspective view thereof on a reduced scale as installed on an air mattress, the broken lines being shown for illustrative purposes only and forming no part of the claimed design.

FIG. 1

FIG. 2

FIG. 3

FIG. 4

FIG. 5

FIG. 6

FIG. 8

FIG. 7

FIG. 9

FIG. 10

FIG. 11

FIG. 12

FIG. 13

FIG. 14
